WILLISTON CONNER, OF RENSSELAERVILLE, NEW YORK.

Letters Patent No. 78,787, dated June 9, 1868.

IMPROVEMENT IN HOP-POLES.

The Schedule referred to in these Letters Patent and making part of the same.

TO ALL WHOM IT MAY CONCERN:

Be it known that I, WILLISTON CONNER, of Rensselaerville, in the county of Albany, and State of New York, have invented a new and useful Improvement in Hop-Poles; and I do hereby declare that the following is a full, clear, and exact description thereof, which will enable those skilled in the art to make and use the same, reference being had to the accompanying plate of drawings, forming part of this specification.

Figure 1 represents my improved hop-pole, with part of the arrangement in section, taken in the lines $x x$, figs. 2 and 3.

Figure 2 is a detached view of one of the holding-rings to secure accessory poles.

Figure 3 is a detached view of another holding-ring to secure the accessory poles.

Similar letters of reference indicate corresponding parts.

This invention relates to an improvement in hop-poles, and consists in attaching three accessory poles to the top of a main pole set in the ground by means of holding-collars, through which the lower ends of the poles pass, as hereinafter described.

A represents a main hop-pole set in the ground, and B B are two iron collars, one larger than the other, and placed one above the other on the taper end of the pole A, so as to set a short distance apart. The inside of the collars B B have sharp points, $a a$, to strike into the wood, and prevent them from turning on the pole.

The collars B B' are made with three rings, $a a'$, on the outside, placed at the corners of an equilateral triangle, and the rings a' of the lower collar B' are smaller than those of the upper collar B, in order that the taper ends of three detached hop-poles C shall fit in them, and be held firmly when the poles are set. The inside of these rings $a a'$ is made round or convex, and the upper collar being larger than the lower, the upper part of the accessory poles C may be made to flare apart as widely as desired, thus regulating the strain of the leverage.

By means of the rings $a a'$, I am enabled to set the poles C in a vertical position, instead of having them flare apart.

Having thus described my invention, I claim as new, and desire to secure by Letters Patent—

The combination of the large and small rings B B', constructed as described, that is to say, each having three openings a on the outer parts, and one central opening with teeth, and used with the poles A and C C C as and for the purposes specified.

WILLISTON CONNER.
